JEWELRY FINDING

Charles Letzo, 2105 Morningside Drive,
Safety Harbor, Fla.

Filed July 19, 1960, Ser. No. 61,423

Term of patent 14 years

(Cl. D45—19)

Fig. 1.

Fig. 2.

Fig. 3.

Fig. 5.

The broken line showings of the ear ring and the pin body are for illustrative purposes only.

The dominant features of my design are shown in full lines.

I claim:

The ornamental design for a jewelry finding, as shown and described.
